UNITED STATES PATENT OFFICE

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS

FEEDING MECHANISM FOR SEWING MACHINES

Application filed September 26, 1921. Serial No. 503,430.

The invention relates to new and useful improvements in feeding mechanisms for sewing machines, and more particularly to a feeding mechanism which is adapted to be used in a work supporting arm.

An object of the invention is to provide a feeding mechanism for a work supporting arm which is so constructed that the feed dog may be raised and lowered with little or no tilting of the feed dog from front to rear or vice versa.

A further object of the invention is to provide a feeding mechanism of the above character wherein the feed bar extends substantially the entire length of the projecting arm and is pivoted at the inner end thereof so that the swinging movements of the feed bar to raise and lower the feed dog will cause said feed dog to move bodily vertically with little or no tilting of the feed dog from front to rear or vice versa.

A still further object of the invention is to provide a feeding mechanism of the above type wherein the feed bar is raised and lowered and is moved endwise by levers, which levers extend respectively to points within a vertical frame member carrying the work supporting arm so that eccentric straps may be connected to and operate said respective levers.

These and other objects will in part be obvious and will in part be hereinafter more fully disclosed.

In the drawings which show by way of illustration one embodiment of the invention:—

Figure 1 is a view in vertical section showing a portion of a sewing machine embodying my improvements;

Fig. 2 is a plan view of the work supporting arm and the upper end of the vertical frame member carrying the arm with the cover plate and throat plates removed to show the parts beneath the same;

Fig. 3 is a sectional view on the line 3—3 of Fig. 2;

Fig. 4 is a sectional view on the line 4—4 of Fig. 2;

Fig. 5 is a sectional view on the line 5—5 of Fig. 2; and

Fig. 6 is a sectional view on the line 6—6 of Fig. 1.

I have shown the invention as applied to a sewing machine of the type disclosed in the patent granted Lansing Onderdonk, December 18, 1906, No. 839,077. Said machine has a frame member extending horizontally and parallel with the overhanging arm. The machine has been illustrated only in part in the drawings, and reference may be made to said patent for a better understanding of the complete machine.

In the present drawings, the horizontally extending member referred to is indicated at 1 and in said horizontally extending member is an operating shaft 2. Projecting vertically from this horizontally extending frame member 1 is a vertical frame member 3. The shaft 2 projects into this vertically extending frame member 3. Formed integral with the vertically extending frame member 3 is a work supporting arm 4. Said work supporting arm 4 is provided with a bearing bracket 5 at its outer end which is preferably formed integral with the work supporting arm. There is also a bearing bracket member 6 at the inner end of this work supporting arm which is detachably secured to the arm by means of screws 7, 7 (see Fig. 6). The machine as shown, is a machine of the type wherein the material is fed off from the work supporting arm.

The material is held on the work supporting arm by means of a presser foot 8 carried by a presser bar 9. Directly in front of the presser foot in the present embodiment of the invention, is a feeler 9' for overlapping and interfolding the edges of a tubular 90

article so that they may be directly beneath the presser foot.

The stitching mechanism preferably consists of a pair of needles 10, 10 with which 5 cooperates a pair of thread carrying loopers 11, 11. These loopers are carried by a looper support 12 mounted on the end of a shaft 13 which is mounted in the brackets 5 and 6 so that it may not only oscillate but move end- 10 wise in the brackets. The looper supporting shaft 13 is oscillated and moved endwise by means of a lever 14. Said lever 14 cooperates with a crank pin 15 on the operating shaft 2, and at its upper end engages a ball 15 stud 16 carried by the outer end of an arm 17 (see Fig. 2) which is rigidly clamped to the looper supporting shaft 13. Intermediate the ends of the lever 14 there is a sleeve 18 to which is attached a fulcrum arm which 20 serves as a fulcrum for the lever 14, and this arm is so mounted and constructed that the lever can move endwise as well as oscillate, and thus it is that the lever imparts both the loop taking and shedding movements to the 25 loopers, and a needle avoiding movement.

The screw 19 is for the purpose of shifting the connection of the fulcrum arm with the lever 14. This looper mechanism for the operating lever forms no part of the present 30 invention, but is shown, described and claimed in my co-pending application filed of even date herewith, Serial Number 503,429.

My improved feeding mechanism consists of a feed bar 20 which extends longitudinally 35 of the work supporting arm 4, and from a point over the bracket 5 to the inner end of the arm and inner side of bracket 6. This lever 20 carries a feed dog 21 which is secured to the lever by means of a screw 22. The 40 lever at the right hand end thereof is forked as indicated in Fig. 2 at 23. The members of the forked end 23 straddle the upper end 24 of the bracket 6. (See Fig. 6.) A pin 25 is carried by the forked end 23, and said pin intermediate its ends, is slabbed to form a reduced section 26. The upper end 24 of the bracket 6 is provided with a slot or recess 27 shown in dotted lines in Fig. 1. The reduced section 26 of the pin 25 slides in this 45 slot or recess 27. A screw 28 passes down through the upper end 24 of the bracket at the left hand side thereof as viewed in Fig. 1, and beyond the range of the sliding movements of the pin 25. The feed bar oscillates 50 on this pin 25 for giving to the feed dog its rising and falling movements. The pin slides in a slot or groove 27 and thus permits the feed bar to move endwise for giving to the feed dog its feeding movements. It will 55 be noted that the pivotal support for the feed bar 20 is at the extreme right hand end of the work supporting arm 4, and when the feed bar swings about said pivot to raise and lower the feed dog, the length of the radius 60 on which the feed dog swings is so great,

that the feed dog will practically be raised and lowered bodily without any tilting movements from front to rear or vice versa. This is extremely important for it holds the feed dog substantially horizontal throughout its feeding movements, and thus it is that the feed dog becomes effective to feed the material both in front and in rear of the needles and in the region penetrated by the needles. 70

The feed bar 20 is raised and lowered by means of a lever 29. This lever 29 is fulcrumed on a pin 30 mounted in the work supporting arm 4 and held therein by means of a screw 31 (see Fig. 4). The pin 30 has an eccentric section 32 which serves as a fulcrum portion for the lever 29. The screw 31 is also a set screw to hold the pin 30 from turning, and said pin is provided with a slot 33 adapted to receive a screw driver. By loosening the set screw 31, the pin 30 may be turned so as to shift the position of the eccentric portion 32 and thus raise or lower the fulcrum point of the lever 29. This serves as a means for raising or lowering the feed dog. 80

At the inner end of the lever 29 is a pair of links 34, 34 (see Fig. 3). These links 34, 34 are located on opposite sides of the looper supporting shaft 13 and are connected by means of a pivot pin 35 with the lever 29. 90

The links 34, 34 at the upper end thereof are connected to the feed bar 20 by means of a pivot pin 36. The lever 29 extends rearwardly from the pivotal support 30 into the upper end of the vertically disposed frame member 95

3 and is there pivoted at 37 to an eccentric strap 38 which cooperates with an eccentric on the operating shaft 2. 100

The feed bar is moved endwise by means of a lever 39. The lever 39 is pivotally supported on a pin 40 (see Fig. 5). This pin 40 is carried by the work supporting arm 4 and is held in place by a set screw 41. Said lever at the right hand end thereof projects into the vertically disposed frame member 3 and is 105 pivoted at 42 to an eccentric strap 43 which cooperates with the eccentric on the operating shaft 2. The lever 39 extends to the left of the pivotal point 40 where it is up-turned and slotted as indicated at 44. The feed bar 20 at the right hand end thereof is provided with a downwardly extending projection 45. A link 46 is pivoted at 47 to this downwardly extending projection 45 and is also pivoted to a bolt 48 which can be shifted in the slot 44. As 110 the lever 39 is oscillated, the link 46 will be moved endwise and this will move the feed bar endwise. The extent of movement imparted to the link depends upon the position of the bolt 48 in the slot 44. By adjusting this bolt, the throw of the feed dog may be readily varied. 115

The upper portion of the work supporting arm and the vertical frame member are open, and are closed by means of a cover plate 49. 120

The throat plate 50 is secured to the work supporting arm, and the loopers are enclosed by means of a cap plate 51.

The operation of my device will be obvious from the description which is given above. The feed bar is moved endwise by a lever which projects into the vertically disposed frame member and by an eccentric strap located therein, and this endwise movement may be varied by shifting the connection between the link and the lever. The feed dog is raised and lowered by another lever which extends into the vertically disposed frame member and by an eccentric strap located therein. As said lever oscillates, it raises and lowers the outer end of the feed bar and said feed bar swings about a pivot which is disposed such a distance from the feed dog that the feed dog has a movement vertically, with little or no tilting movement, so that said feed dog remains substantially horizontal throughout its entire movement.

It is obvious that minor changes in the details of construction and the arrangement of the parts may be made without departing from the spirit of the invention as set forth in the appended claims.

Having thus described the invention, what I claim as new and desire to secure by Letters Patent, is:—

1. In a sewing machine, the combination of a vertically extending frame member, a work supporting arm projecting laterally therefrom, a feed bar extending lengthwise of said arm, a feed dog carried at the outer end of said feed bar, a stationary support at the inner end of said feed bar, said support having a horizontal slot therein, a pivot pin having the central part thereof slabbed and adapted to slide back and forth in said slot, said feed bar being connected to said pivot pin so that said feed bar may swing on said pivot pin as an axis, and said pivot pin can move back and forth with the feed bar, means for swinging the feed bar on its pivot for raising and lowering the same, and means for moving the feed bar back and forth on said stationary support.

2. In a sewing machine, the combination of a vertically extending frame member, a work supporting arm projecting laterally therefrom, a feed bar extending lengthwise of said arm, a feed dog carried at the outer end of said bar, means for pivotally and slidably supporting the inner end of said feed bar on a stationary support, means for swinging said feed bar on its pivot for raising and lowering the feed dog, a lever located in said work supporting arm between said pivotal support for the feed bar and the feed dog carried by said bar, means for oscillating said lever, a link connected to said lever and to said feed bar at a point adjacent said pivotal support for moving said feed bar back and forth on said pivotal support.

3. A sewing machine including in combination a vertically extending frame member, a work supporting arm projecting laterally therefrom, an operating shaft extending into said frame member, a feed bar extending lengthwise of said arm, a feed dog carried at the outer end of said bar, means for pivotally and slidably supporting the inner end of said feed bar on said work supporting arm whereby said feed bar is capable of sliding back and forth and swinging about an axis at the inner end thereof, means operated by said shaft for swinging the feed bar on its pivot for raising and lowering the feed dog, means operated by said shaft for moving the feed bar back and forth on said pivot, said last-named means including a lever fulcrumed in said work supporting arm between the ends of said feed bar, means for oscillating said lever, and a link connecting said lever to said feed bar at a point adjacent the pivotal support for the feed bar.

4. The combination of a vertically extending frame member, a work supporting arm projecting laterally therefrom, an operating shaft extending into said frame member, a feed bar extending lengthwise of said arm, a feed dog carried at the outer end of said bar, means for pivotally and slidably supporting the inner end of said feed bar, means operated by said shaft for swinging the feed bar on its pivot for raising and lowering the feed dog, means operated by said shaft for moving the feed bar back and forth, said means for raising and lowering the feed bar including a lever, a pivot pin located within said work supporting arm and having an eccentric portion on which said lever is fulcrumed, means for holding said pin in adjusted position, links connecting the outer end of the lever to the feed bar, said lever projecting rearwardly into said vertically disposed frame member, and an eccentric strap in said frame member for connecting said operating shaft to said lever.

5. The combination of a vertically extending frame member, a work supporting arm projecting laterally therefrom, an operating shaft extending into said frame member, a feed bar extending lengthwise of said arm, a feed dog carried at the outer end of said bar, means for pivotally and slidably supporting the inner end of said feed bar, means operated by said shaft for swinging the feed bar on its pivot for raising and lowering the feed dog, means operated by said shaft for moving the feed bar back and forth, said pivotal supporting means for the feed bar including a bracket detachably connected with said work supporting arm at the inner end thereof, said bracket having a slot in the upper portion thereof, a pivot pin having the central part thereof slabbed and adapted to slide back and forth in said slot, said feed bar having its inner end forked to engage said pivot pin.

6. A sewing machine including in combination, a cylindrical work supporting arm, a feed bar extending lengthwise of said arm, a feed dog carried at the outer end of said bar,
5 means for pivotally and slidably supporting the inner end of said feed bar, means for swinging said feed bar on its pivot for raising and lowering the feed dog, and means for moving the feed bar back and forth including an oscillating lever located in said work supporting arm and having a slotted end, and a link adjustably connected to said slotted end of the lever and to said feed bar at a point in rear of the pivotal support at
10 the inner end thereof.
15 In testimony whereof, I affix my signature.

JAMES R. MOFFATT.
